UNITED STATES PATENT OFFICE.

FRANK D. O'KEEFE, OF PHILADELPHIA, NEW YORK, ASSIGNOR TO NETTIE L. O'KEEFE, OF SAME PLACE.

FOLDING CHAIR.

SPECIFICATION forming part of Letters Patent No. 616,346, dated December 20, 1898.

Application filed July 27, 1898. Serial No. 687,034. (No model.)

To all whom it may concern:

Be it known that I, FRANK D. O'KEEFE, a citizen of the United States, residing at Philadelphia, in the county of Jefferson and State 5 of New York, have invented certain new and useful Improvements in Folding Chairs; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to certain new and useful improvements in folding chairs; and it has for its object the provision of an adjustable reclining-chair so constructed as to admit of its being readily assembled without 20 requiring either special skill or tools of any kind and when prepared for either shipment or transportation capable of being folded within small compass.

25 To these ends and to such others as the invention may pertain the same consists in the peculiar construction of the chair and in the novel combination, arrangement, and adaptation of parts, all as more fully hereinafter described, shown in the accompanying drawings, and then specifically defined in the appended claims.

30 The invention is clearly illustrated in the accompanying drawings, which, with the letters of reference marked thereon, form a part 35 of this specification, like letters of reference indicating the same parts throughout the several views, and in which drawings—

Figure 1 is a perspective view of a chair constructed in accordance with my invention, 40 parts being broken away in order to more clearly illustrate the connection of the seat with the corner-posts. Fig. 2 is a detailed view in perspective, upon an enlarged scale, showing a portion of the chair-seat and corner-post, the same being shown in their relative positions, but slightly separated. Fig. 45 3 is a like view of the chair-seat with the front and rear rails or cross-bars hinged thereto, the said rails being shown as folded back 50 against the under face of the seat.

Reference now being had to the details of

the drawings by letter, A and B designate the front and back legs, respectively, which constitute the front and rear corner-posts of the chair.

55 C C indicate the side rails, and D D the arms, the said side rails and arms being in the present instance shown as connected by means of ornamental posts a a, though it is at once evident that any other forms of ornamental work, such as is commonly employed in the construction of chairs, may be substituted for these posts.

60 The rear ends of the arms D are extended for a considerable distance beyond the rear posts B, and directly beneath these rearwardly-extending portions of the arms is secured a metallic fixture or plate E, having its upper edge notched, as shown at b b, these notches being designed to receive a rod F, 70 the ends of said rod being screw-threaded to receive the enlarged portions or heads F'.

75 G is the seat-frame of the chair, to the rear edge of which is hinged the chair-back H, which when the chair is in use inclines against the bar F, the angle of inclination depending upon the set of notches b, in which the bar is placed. It will be observed that the diameter of the enlarged portions or knobs F' is greater than the space intervening between 80 the notched bar and the lower face of the chair-arm. By this construction it is rendered impossible to remove the bar F from the chair without first removing one of the knobs from the end of the bar, as will be readily understood, thus rendering the accidental displacement of the bar impossible.

85 It will be observed that my chair is constructed in four sections—viz., the two side sections, each of which consists of a front 90 and rear post or leg, an arm D, a side rail, and the notched plate to receive the cross-bar. The other sections consist of the seat-frame and the chair-back, which is hinged to the rear edge of the seat-frame.

95 J and K represent the front and rear rails of the chair, said rails being hinged at their upper edges to the under faces of the front and rear edges of the seat-frame, as shown. Both the front and rear rails J and K are provided at their ends with hooked metallic plates M and N, which extend outwardly from

the ends of the rails and are adapted to enter recesses or slots O and P, formed for their reception in the inner faces of the front and rear legs or posts of the chair, as shown, the notches m and n in said plates being adapted to engage metallic bars o within the slots in the legs. The advantages of this construction will be at once evident, as in assembling the parts of the chair it is simply necessary to that the metallic plates at the ends of the rails J and K, which are hinged to the chair-seat, should be inserted in the recesses or slots in the front and rear legs or posts of the chair, when by gravity the hooked portions of the plates will engage the metallic rods or keepers o, and thus securely lock the parts together. The advantage gained by hinging the front and rear rails to the under face of the seat-frame will be at once evident, as by this construction the rails when the seat-frame is detached from the sides of the chair may be folded back closely against the lower face of the seat-frame, thus occupying but little space, and by removing the rod F the back of the chair may be folded closely against the upper face of the seat-frame, thus permitting the chair to be folded within the

smallest possible compass for convenience in either storage or shipping.

Having thus described my invention, what I claim to be new, and desire to secure by Letters Patent, is—

1. A chair-seat having rails hinged thereto, the corner-posts or legs of the chair slotted as described, in combination with hooked metallic plates carried by the ends of the rails and adapted to engage keepers located within the slots in the posts, substantially as described and for the purpose specified.

2. In a folding chair, the combination with the chair-bottom, the front and rear rails hinged thereto, the hooked metallic plates, the side rails and arm-rests with legs formed in one section, each leg having a recess carrying a pin, the hooked metallic plates carried by the ends of the folding rails, and adapted to fit in said sockets, and over the pins, as shown and described.

In testimony whereof I affix my signature in presence of two witnesses.

FRANK D. O'KEEFE.
